UNITED STATES PATENT OFFICE

2,491,713

RADIO AERIAL FOR USE ON VEHICLES

Charles Molyneux Carington, George William Shoobert, and Walter Jonathan Pickett, London, England, assignors to K. L. G. Sparking Plugs Limited, London, England, a British company

Application October 13, 1947, Serial No. 779,507
In Great Britain June 25, 1946

2 Claims. (Cl. 250—33)

1

This invention relates to radio aerials for use on vehicles and has for its object to provide an improved construction whereby the making of the electrical connections with it is facilitated, the mounting on or attachment to the vehicle is also facilitated, and the aerial can be readily adjusted to an extended or "receiving" position or swung down into a stored position.

According to the present invention a radio aerial assemblage for a motor vehicle comprises an insulating base on which the aerial is mounted and which constitutes the attachment to the vehicle, a pair of electrical terminals mounted on the base, an electrical connection from one of said terminals to the aerial and a second electrical connection from the other terminal adapted to engage the body of the vehicle.

Preferably the insulating base is formed with a socket, and said terminals have each a spring finger extending across said socket to make electrical connection with the core and sheathing respectively of a screened cable inserted in the socket.

According to another feature of this invention a radio aerial assemblage as above set forth is used in combination with a screened cable having a metal ferrule on the sheathing to be engaged by one of said spring fingers, and a nipple on the core to be engaged by the other of said spring fingers. The nipple may be formed with a shoulder to be engaged by a spring finger and to be retained thereby in the socket.

The invention also concerns other novel features in the mechanical construction and arrangement of the assemblage, and of the mounting of the aerial rod on the assemblage by a resiliently controlled joint which permits displacement of the aerial in the event of it fouling, say, a garage roof, without damage.

In the accompanying drawings which illustrate one embodiment of this invention,

Figure 1 is a side elevation of the assemblage, partly in section,

Figure 2 is a plan of Figure 1,

Figure 3 is an elevation in central section to a larger scale, and

Figure 4 is a sectional view on the line 4—4 of Figure 3.

In the construction illustrated, the aerial assemblage is mounted on a metal panel of a vehicle indicated at 10 in Figures 1, 2 and 3. A hole is made in the panel to receive a block of insulating material 11 which lies mainly on one side of the panel 10, but has an extension-piece 12 passing through the hole and engaging a sec-

2

ond block of insulating material 13. These two blocks have coaxial bores and are mounted on a sleeve 14 which is screw-threaded at one end 15 and has a disc-like member 16 secured on its other end. A nut 17 when screwed on to the sleeve 14 clamps the two blocks 11 and 13 on to the panel 10 and thereby secures them rigidly thereon. A soft packing member 18 may be interposed between the block 11 and the panel to assist in making a weathertight joint on the outer side of the panel.

A shaft 19 extends through the sleeve 14 and is rotatable therein, and on the outer end 20 of this shaft there is secured on it an aerial rod 15 which extends radially from the shaft. A metal block 21 is secured on the end of the shaft and is formed with a recess 22 to receive a conical member 23 which is formed with an annular seating 24 which is of substantially circular cross-section. A tubular member 25 is formed with a cooperating seating to engage the annular seating 24, and it is resiliently held in engagement therewith by means of a spring 26 which presses it thereon. The spring is seated at one end on an internal shoulder 27, and at its other end on a block 28 which is slidable within the tube 25 but is anchored to the portion 23 by a flexible steel cable 29. With this construction the tube 25 is normally held firmly in engagement with the seating 24, but it can be displaced by rocking on the seating against the compression of the spring 26. At the upper end of the tube 25 there is mounted an extension tube 30 (see Figure 1) and this latter contains a telescopically adjustable rod 31 which is frictionally retained in an extended or retracted position by a suitable shaping of its inner end 32.

The part 23 is locked in the part 21 by a retaining screw 33 (see Figure 3), and there are also mounted on this part two locating studs 34 which are adapted to engage teeth 35 formed on the member 16 so as to retain the shaft, and therefore the aerial rod in any angular position to which it may be adjusted, in particular an extended or receiving position or in a stored position. In order to permit disengagement of the studs 34 from the teeth 35, the shaft 19 is movable axially against the action of a spring 36 (see Figures 1 and 2) located between the nut 17 and a bush 37 secured on the shaft and carrying a handle or knob 38 by which the shaft can be moved endwise and rotated.

The aerial rod including the parts 25, 23 and 21 are all made of metal and are mounted on 55 the metal shaft 19 so that they are electrically

connected together, and the electrical connection from the aerial to the lead-in wire is effected in the following manner as shown particularly in Figures 2 and 4. The lead-in wire is constituted by a screened cable comprising a central core or conductor 39 surrounded by insulation 48 and an outer sheath 41 or a screen of braided metal wire. There may also be an outside insulating covering 42 around the metal sheath. To reduce the electrical capacity between the conductor 39 and the sheath 41, the conductor is made of very small diameter, preferably being so fine that it cannot be conveniently attached to a screw terminal in the ordinary way. It is therefore secured at its end in a nipple 43 (see Figure 4) which is an inwardly directed shoulder 44 and this end is mounted in an insulating tube 50. In order to provide good electrical contact with the metal sheath 41, this is opened out over a metal tube 45 and a ferrule 46 is provided around it, the sheath 41 preferably being soldered to the parts 45 and 46, and these parts are also secured to the insulating tube 50 so that the end of the cable provides two exposed contacts, namely the nipple 43 and the ferrule 46 which are spaced apart longitudinally on it. The insulating block 13 is provided as shown in Figure 2 with two slots 47, 48 and in the slot 47 there is located a spring finger 49 to engage the nipple 43 at the shoulder 44. It thereby makes electrical contact therewith and prevents the cable from being withdrawn until the spring finger is depressed clear of the shoulder. This spring finger 49 is formed integrally with a washer 51 (see Figures 2 and 3), the washer 51 being clamped between the insulating block 13 and a metal washer 52 by the nut 17 so that electrical connection is provided from the aerial rod through the shaft 19, sleeve 15, washer 51 and finger 49 to the conductor 39 of the lead-in wire.

The slot 48 receives a similar spring finger 53 which engages the ferrule 46, and is formed integrally with a washer 54 (see Figure 3) which is clamped between the block 13 and the panel 10 so as to make electrical contact with the panel, thereby providing an "earth" connection to the vehicle as a whole.

It will be seen that the above construction provides an aerial rod or mast which can be adjusted to an upright position for receiving, or swung down into a stored position when not in use. In the event of the aerial mast fouling an obstruction when erected, it can rock on its annular seating 24 thereby avoiding damage to the mast; but such rocking movement compresses the spring 26 so that the mast returns automatically to its proper position when freed from the obstruction. Furthermore the electrical connections to the aerial are made simply by inserting the screened lid into engagement with the two spring fingers 49 and 53 respectively. It can be disengaged therefrom simply by depressing the spring finger. Finally the whose assemblage is readily secured in place on the vehicle since it is necessary only to make the necessary hole in the panel 10 and clean the surface thereof so that the washer 54 can make electrical contact with it. The sleeve 14 with the block 11 and packing 13 on it is inserted in place and the block 13 is then threaded on the sleeve and the nut 17 screwed up to mount the whole assemblage securely in place.

We claim:

1. A radio aerial assemblage for a vehicle comprising in combination a metal sleeve screw-threaded at one end and provided with a radial shoulder at its other end, an insulating block on said sleeve located against said shoulder, a second insulating block on said sleeve formed with parallel axially extending slots and with a transverse bore opening into said slots, a metal washer between said insulating blocks, a spring-finger on said washer extending along one of said slots across the said transverse bore, a second spring-finger in the other of said slots extending from the said transverse bore to the other end of said second insulating block, a second metal washer on said sleeve in electrical connection with said second finger, a nut screwed on said sleeve and engaging said second washer, a single-core insulated cable, a metal screening sheath thereon, a nipple secured on the end of the core of said cable, a metal ferrule secured on said sheath, an insulating tube separating said ferrule and said nipple, said cable-end being adapted to enter said transverse bore and effect engagement of said ferrule with one of said spring fingers and of said nipple with the other of said spring-fingers, a shaft rotatable in said sleeve, means for locking said shaft in any of a plurality of angular settings and an aerial rod secured on said shaft and extending laterally therefrom.

2. A radio aerial assemblage for a motor vehicle comprising in combination an insulating base adapted to be mounted in a panel of the vehicle, a metallic elbow member mounted on said insulating base by a threaded member passing through said base, first engaging means formed on said elbow member, an elongated hollow metallic member, second engaging means on said elongated hollow metallic member, said first and second engaging means being adapted to engage each other and when engaged to support the said elongated hollow metallic member with its axis substantially at right angles to the axis of the threaded member, resilient means within said elongated hollow metallic member and a flexible cable attached at one end to the aforesaid elbow member and at the other end to the aforesaid resilient means, whereby said cable and said resilient means strain the aforesaid first and second engaging means to remain in engagement.
